Attorney.

UNITED STATES PATENT OFFICE.

ADOLPH M. DEUTSCH AND WILLIAM V. DUPRE, OF NEW YORK, N. Y.

INDICATOR.

1,402,220.

Specification of Letters Patent.

Patented Jan. 3, 1922.

Application filed August 16, 1921. Serial No. 492,750.

To all whom it may concern:

Be it known that we, ADOLPH M. DEUTSCH and WILLIAM V. DUPRE, citizens of the United States, residing at New York, in the 5 county and State of New York, have invented certain new and useful Improvements in Indicators, of which the following is a full, clear, and exact specification.

This invention relates to indicators or tags 10 for faucets and has for its object to provide a simple form of label which may be readily attached to hot water and cold water faucets to distinguish between them and prevent such mistakes as drinking impure 15 water from a hot water faucet, and the inadvertent discharge of scalding water upon a bather.

A special object is to provide an indicator 20 or label which fits over the nozzle of a faucet so as to prevent accidental turning of said indicator thereon which might bring the indicia to a position at the side or rear of the faucet where it could not be clearly seen and consequently defeat the purpose of 25 the device. Other objects will appear as the description proceeds.

The invention contemplates the provision 30 of labels or tags which may be made of inexpensive material and provided with simple attaching means, such as flexible arms adapted to be bent around the stems of faucets. Said indicators are especially adapted for use by travelers who are obliged to stop at 35 hotels not equipped with the improvements of modern plumbing, such as permanent indicia on the faucets. These detachable indicators may, however, be also used in homes for marking the faucets in the bath rooms, kitchens, or elsewhere. The invention 40 will be further herein described in connection with the accompanying drawings, which constitute part of this specification, and then more specifically defined in the claims at the end of the description.

45 In the accompanying drawings, wherein similar reference characters are used to designate corresponding parts throughout the several views:

Figure 1 is a front elevation of a faucet 50 showing one of our indicators applied thereto.

Figure 2 is a side view of the faucet showing the indicator in section.

Figure 3 is a detailed perspective view of 55 one form of the indicator, the attaching

arms being shown spread apart in dotted lines, and

Figure 4 is a detailed plan view of a modified form of indicator.

In Figures 1 and 2, 1 indicates a faucet 60 of usual form having a nozzle 2, a stem 3 provided with a handle 4, and a nut 5 around the base of the stem. The indicator comprises a split ring portion 6 having flexible arms 7 adapted to be bent around or just 65 below the nut 5, as clearly illustrated in Figures 2 and 3, and a channeled skirt portion 8 depending from the front of said ring to fit over the nozzle 2 of the faucet.

The arms 7 may have tapered ends to 70 overlap one another, as at 9 in Figure 3, or said arms may be made to abut against one another, as at 10 in Figure 4. The indicia 11, such as "Hot" or "Cold," in each instance is preferably placed on the front portion of 75 the ring 6 just above the skirt portion 8, but said indicia may be placed on said skirt portion, as suggested in Figure 4. It will be noted that the channeled skirt portion 8 fits over the nozzle 2 like a saddle and is retained in position thereon by gravity so that the indicia 11 will always be maintained in clear view at the front, there being no danger of the tag or label becoming accidentally displayed or rotated around the stem 3 of 80 the faucet.

We claim:

1. A faucet indicator having a ring-shaped portion to detachably encircle the stem of a faucet, and a channeled portion 90 extending radially from said ring-shaped portion to saddle the nozzle of the faucet for the purpose specified.

2. A faucet indicator comprising a ring-shaped portion having flexible arms for detachably encircling the stem of a faucet, and a channeled depending portion to saddle the nozzle of the faucet for the purpose specified. 95

3. A faucet indicator comprising a ring-shaped portion having flexible arms with tapered ends adapted to overlap one another for detachably encircling the stem of a faucet, and a channeled depending portion to saddle the nozzle of the faucet for the purpose specified. 100

In testimony whereof we have signed our names to this specification.

ADOLPH M. DEUTSCH.
WILLIAM V. DUPRE.
